UNITED STATES PATENT OFFICE.

WILLIAM JOHNSTON, OF MILLERSBURG, OHIO, ASSIGNOR OF ONE-HALF TO
M. V. LEGUILLOON, OF MILLERSBURG, OHIO.

FENDER FOR CARS.

SPECIFICATION forming part of Letters Patent No. 733,048, dated July 7, 1903.

Application filed August 30, 1902. Serial No. 121,649. (No model.)

To all whom it may concern.

Be it known that I, WILLIAM JOHNSTON, a citizen of the United States, residing at Millersburg, in the county of Holmes and State of Ohio, have invented a new and useful Fender for Cars, of which the following is a specification.

This invention relates to car-fenders; and it consists of a supporting-frame pivotally connected to a car-truck independent of the car-body and which will not be affected by any springing movement of the body, but will always remain in contact with the track, said frame being provided with a tilting netting-frame adapted to be tilted by the weight of a person falling upon or being thrown thereon, and thus elevate them from the track, and which will also be automatically maintained in its elevated position, and thus protect the occupants and prevent injury to them.

The invention consists in certain novel features of construction, as hereinafter shown and described, and specified in the claim.

In the drawings illustrative of the invention, Figure 1 is a vertical longitudinal section of a portion of a car-truck and car-body with the improved device applied thereto. Fig. 2 is a plan view of a portion of a car-truck and a plan view of the improved device applied.

The device may be applied to any form of railway-car truck, but will be more particularly applicable to electric-railway cars, and for the purpose of illustration the invention is shown applied to a conventional form of truck usually employed beneath cars of this character, 10 representing the truck-frame, 11 the forward axle, 12 the forward truck-wheels, and 13 a portion of a car-body, all these parts being of the usual construction.

The improved device consists of a supporting-frame constructed of spaced side members 14 15, preferably united at their rear ends and pivotally connected at 16 directly to the truck-frame 10 and remote from the body portion of the car and just in advance of the forward axle 11, as shown, the object being to prevent any springing movement of the car-body from affecting the supporting-frame,

and thereby overcome any tendency of the supporting-frame to leave the track.

The netting-frame preferably consists of an oblong rectangular frame 17, upwardly curved at its lower end and provided with a rubber or other yieldable member upon the lower end, preferably in the form of a roller 18, as shown.

The framework 17 is provided with an intermediate transverse connecting member 19, located at a considerable distance below its center, as shown, and is also provided with spaced rods 20, conforming to the curvature of the frame and forming the "netting" to engage the persons and support them when caught by the fender.

If preferred, the netting may be formed of ropes, wire, or other yieldable material interwoven or otherwise arranged and connected to the frame 17 instead of the bars 20, as the results produced would be the same, and I do not, therefore, wish to be limited to any specific form of the surface of the frame 17.

The curved forward ends of the bars 14 and 15 are coupled to the intermediate transverse bar 19 by means of the clips 21, which form journals in which the netting-frame will swing vertically with relation to the supporting members 14 15, as indicated by dotted lines in Fig. 1.

A transverse brace-bar 22 may be secured to the spaced members 14 15 of the supporting-frame to prevent their lateral displacement at their forward ends, as shown.

It will be noted that the frame 17 is extended laterally some distance beyond the outside lines of the truck-frame 10 and will correspond in width or be somewhat wider than the body 13 of the car, so that it will sweep the track clear of all objects with which the car-body would be liable to engage.

23 and 24 are springs, which are connected by their upper ends to the studs 25 26, located on the members of the supporting-frame 14 15, and by their lower ends in any suitable manner to the frame 17 or its attachments near the lower end of said frame or at any point below its pivot-joint, so that the springs when the netting-frame is depressed exert a constant pulling force to hold

the same normally in its operative position, as indicated in full lines in Fig. 1, while one or more chains 29 will be arranged between the upper ends of the netting-frame and the 5 supporting-frame to limit the downward movement of the forward end, as will be obvious. These chains 29 may be adjusted to limit the downward movement of the roller 18 and the forward end of the netting-frame. 10 When thus constructed, any object with which the netting-frame comes in contact, if it be large enough to extend above the pivotal point 19, will exert a force against the upper portion of the netting-frame and overcome 15 the resiliency of the springs and tilt the upper end of the frame downward and correspondingly elevate the lower end, as indicated in Fig. 1 in dotted lines, thus elevating the object upon the frame clear of the 20 track.

It will be noted that the relative locations of the ends of the springs 23 24 are such that when the netting-frame is in its elevated position the springs will be elevated above the 25 pivotal line 19, so that they will exert their force after the elevation of the netting-frame. To maintain it in such elevated position, prevents the object which is caught by the netting-frame from again coming in contact with 30 the track, and consequently being injured by the wheels.

The members 14 15 of the supporting-frame are themselves supported from the track by flanged wheels 31 32, connected to the side 35 members by hangers 33 34, which are located near the rear end of the frame and at the nearest possible point to the forward truck-

wheels 12, as shown in Figs. 1 and 2, so that a comparatively short distance occurs between the wheels 31 32 and the wheels 12 40 and a comparatively long distance between the wheels 31 32 and the netting-frame 17. This arrangement also provides a very sensitively-acting device, much more so than in structures wherein the bearing-wheels are located 45 beneath or in close proximity to the netting-frame.

The parts will preferably be made of steel, suitably braced and supported, and may be modified and changed in minor particulars 50 without affecting the principle of the invention or sacrificing any of its advantages.

Having thus described the invention, what is claimed is—

A car-fender consisting of a supporting-frame movably connected to a car-truck, a netting-frame pivoted to the supporting-frame, flexible connections between the netting-frame and supporting-frame, and springs secured at one end to the netting-frame below 60 the plane of the pivot-point, and at the other end to the supporting-frame, whereby said netting-frame is normally held in an operative position and maintained in an elevated position when the position of the springs is 65 changed with relation to the pivot-point.

In testimony that I claim the foregoing as my own I have hereto affixed my signature in the presence of two witnesses.

WILLIAM JOHNSTON.
